(57) **CLAIM**

The ornamental design for a stand for display screen as shown and described.

DESCRIPTION

Figure 1.1 is a front, top and right side perspective view of a stand for display screen, showing our new design; Figure 1.2 is a rear, top and right side perspective view thereof;

Figure 1.3 is a front elevation view thereof;

Figure 1.4 is a rear elevation view thereof;

Figure 1.5 is a left side elevation view thereof, the right side elevation view being a mirrored image thereof;

Figure 1.6 is a top plan view thereof;

Figure 1.7 is a bottom plan view thereof;

Figure 1.8 is a rear, top and right side perspective view thereof, shown in an environment of use;

Figure 1.9 is another rear, top and right side perspective view thereof, shown in an environment of use;

Figure 1.10 is a left side elevation view thereof, shown in an alternate position;

Figure 1.11 is another left side elevation view thereof, shown in an alternate position; and,

Figure 1.12 is another left side elevation view thereof, shown in an alternate position.

The broken lines shown in Figures 1.7 and 1.10-1.12 illustrate portions of the stand for display screen that form no part of the claimed design. The broken lines illustrating the display screen in Figures 1.8-1.9 are environment, while the remaining broken lines in Figures 1.8-1.9 illustrate portions of the stand for display screen that form no part of the claimed design.

1 Claim, 12 Drawing Sheets
